[57] CLAIM

The ornamental design for an exerciser for attachment to door or the like, as shown and described.

DESCRIPTION

FIG. 1 is a front perspective view of an exerciser for attachment to door or the like, showing my new design;

FIG. 2 is a top plan view thereof;

FIG. 3 is a left side elevational view thereof;

FIG. 4 is a right side elevational view thereof; and

FIG. 5 is a front elevational view thereof, the side opposite being substantially a mirror image.

FIG. 1
